UNITED STATES PATENT OFFICE.

JOHN ST. AMAND, OF BROCKTON, MASSACHUSETTS, ASSIGNOR TO WILLIAM B. ARNOLD, OF NORTH ABINGTON, MASSACHUSETTS.

DESIGN FOR A HINGE.

SPECIFICATION forming part of Design No. 34,246, dated March 19, 1901.

Application filed December 8, 1897. Serial No. 661,205. Term of patent 7 years.

To all whom it may concern:

Be it known that I, JOHN ST. AMAND, a subject of the Queen of Great Britain, residing at Brockton, in the county of Plymouth and State of Massachusetts, have invented and produced a new and original Design for Hinges, of which the following is a specification, reference being had to the accompanying drawing, forming a part thereof.

10 The drawing shows in perspective a hinge illustrating my design.

The leading or material feature of my design for a hinge consists of the flat leaf members extending in the axial plane of the pintle and having at their outer ends a pair of narrow flanges upturned at a right angle thereto and in alinement with each other, as shown, the side edges of the said leaf members ter-

minating in the plane surfaces of the members.

The drawing shows a hinge A provided with flat leaf members a' a^2 , terminating at their side edges flush with or in the plane of their flat surfaces and having the narrow flanges a in alined pairs upturned at the ends ²⁰ 25 of the leaf members at right angles thereto.

I claim—

The design for a hinge, as herein shown and described.

In testimony whereof I have signed my name to this specification in the presence of two subscribing witnesses.

JOHN ST. AMAND.
